UNITED STATES PATENT OFFICE.

WILLIAM SOWERBY, OF INDIANA, PENNSYLVANIA.

RECEPTACLE.

No. 850,686.

Specification of Letters Patent.

Patented April 16, 1907.

Application filed December 5, 1905. Serial No. 290,472.

To all whom it may concern:

Be it known that I, WILLIAM SOWERBY, a citizen of the United States of America, residing at Indiana, in the county of Indiana and State of Pennsylvania, have invented 5 certain new and useful Improvements in Receptacles, of which the following is a specification, reference being had therein to the accompanying drawings.

10 This invention relates to certain new and useful improvements in receptacles; and the invention relates more particularly to commodes and receptacles for waste products.

15 The primary object of this invention is to provide a novel form of receptacle having an auxiliary outlet and a novel form of supporting-stand. To this end I have devised a receptacle adapted to be used as a commode and have devised novel means for detachably 20 supporting the commode upon a suitable stand, means for supporting the lid of the commode in an open position, and means for confining any odors that may arise from the contents of the commode within the commode until it is emptied.

25 With the above and other objects in view, which will more readily appear as the nature of the invention is better understood, the same consists in the novel construction, combination, and arrangement of parts to be hereinafter more fully described and then specifically pointed out in the claims, and, referring to the drawings accompanying this application, like numerals of reference designate 30 corresponding parts throughout the several views, in which---

Figure 1 is a side elevation of a commode constructed in accordance with my invention. Fig. 2 is a plan of the same. Fig. 3 is a side 35 elevation of a commode, illustrating a lid-supporting device used in connection with the same. Fig. 4 is a plan of the same. Fig. 5 is a fragmentary view of an ordinary commode provided with my improved lid-supporting device.

40 In describing the invention in detail I will consider my improved receptacle as being used as a commode, it being obvious that the same can be readily and conveniently used for other purposes.

45 In practice I construct a receptacle 1, conforming to a bucket, the sides of the receptacle being provided with a pivoted bail or handle 2, whereby it can be easily carried. 50 The upper edge or main opening of the re-

ceptacle is flanged, as at 3, and mounted upon the flanged edge of the receptacle is a seat 4, said seat being provided with resilient curved arms 5 5, which are adapted to engage the flanged edge 3 of the receptacle and retain the seat thereon. In Fig. 1 of the drawings I have illustrated the seat as provided with an ordinary lid or closure 6, while in Fig. 3 a lid or closure 7 is hinged upon the seat, as at 8, and in order to support the lid or closure in an open position, as illustrated by dotted lines in said figure, I employ a lid-supporting device 9, consisting of a piece of wire, which is bent to form a yoke 10, while the ends of the wire are bent, as at 11 11, to embrace the flanged edge 3 of the receptacle, as at 12. The yoke 10 is bent at an angle in order to support the lid or closure in an inclined position when the commode is being used.

55 The commode near its seat is provided with an auxiliary outlet or spout 14, having a hinged lid 15. The contents of the commode are adapted to be emptied through the spout 14, and to facilitate this operation I provide the opposite side of the commode, near its lower edge, with a handle 16, which can be gripped in conjunction with the bail 2 of the commode when emptying the contents of the commode.

60 In connection with the commode I employ a suitable stand or stool 17, which is provided with a plurality of angular clips 18, adapted to engage the flanged lower edge 19 of the commode and prevent said commode from tilting or becoming detached from the stand or stool 17 after it has been once placed in engagement therewith.

65 The seat 4 is adapted to fit snugly upon the commode, whereby when the lid 6 or 7 is closed, together with the lid 15 of the auxiliary outlet 14, it will be impossible for any odors arising from the contents of the commode to escape into the compartment in which it is used. By providing the auxiliary outlet 14 I am enabled to empty the commode without removing the seat 4 or the lids 6 or 7, and the stand or stool 17, which I employ in connection with the commode, is adapted to elevate the same, whereby it can be conveniently used.

70 Such changes in the construction of my improved commode as are permissible by the appended claim may be resorted to without departing from the spirit and scope of the invention.

105

110

What I claim, and desire to secure by Letters Patent, is—

In a device of the class described, a vessel having a lateral flange around its rim, a seat bearing upon said flange and extending beyond the same, a cover hingedly connected to said seat, a resilient clip connected to said seat at the side opposite to the hinge of said cover and yieldably engaging the adjacent portion of said flange, a clip of resilient material connected to said cover at the side adjacent to the hinge thereof and adapted to

yieldably engage said flange, and a support for said lid when in open position and connected to said seat by the same means by which the last-mentioned clip is secured thereto. 15

In testimony whereof I affix my signature in the presence of two witnesses.

WILLIAM SOWERBY.
